BURNER

John H. Sattler, Downey, Calif.

Application March 5, 1935, Serial No. 9,393

6 Claims. (Cl. 158—116)

This invention is a gas burner for a cooking top or the like and has for an object to prevent the flame blowing off the burner ports.

It has a further object of the invention to efficiently mix the air and gas of the combustible mixture and uniformly distribute it to the burner ports so as to insure an even flame of high temperature.

More particularly it is an object of the invention to adapt the burner for discharge of gas into its mixing chamber at high velocity whereby a relatively large volume of air may be drawn into the mixing chamber for so proportioning the air and gas as to insure complete combustion and high flame temperature, with the resulting high velocity of the combustible mixture appreciably reduced before ignition so as to prevent the flame blowing off the burner ports.

It is another object of the invention to baffle the combustible mixture before discharge at the burner ports so as to uniformly mix the air and gas and evenly distribute the combustible mixture.

It is a still further object of the invention to provide an extremely simple and readily manufactured burner structure adapted to baffle and reduce the velocity of the fuel mixture before discharge at the burner ports.

Further objects of the invention will be readily understood from the following description of the accompanying drawing, in which:

Fig. 1 is a side elevation of the burner, partly in axial section.

Fig. 2 is a transverse section on the line 2—2 of Fig. 1.

The burner comprises a body 1 communicating with a fuel pipe 2 which terminates in a usual mixing chamber 3. A valve 4 regulates admission of air to the mixing chamber, and a fuel nozzle (not shown) extends into the mixing chamber through an aperture 5 and supplies fuel such as natural gas, which due to its velocity draws air into the mixing chamber to form a combustible mixture.

To provide an air-gas ratio which will insure complete combustion and high flame temperature, the velocity of the gas at its supply nozzle should be relatively high and the valve 4 should be adjusted to admit a comparatively large volume of air, but the resulting high velocity of the combustible mixture may produce an incomplete mixture of the air and gas, and may unevenly distribute the combustible mixture, and may blow the flame from the burner ports.

The present invention provides for admission of

gas and air so as to insure an efficient combustible mixture, but baffles and retards the high velocity of the fuel mixture so as to prevent the flame blowing off the burner ports and at the same time insure even distribution and high flame temperature.

As an instance of this arrangement burner ports open into a chamber which receives the combustible mixture from pipe 2, the body 1 preferably forming an annular bowl 16 communicating with the fuel pipe 2, with the inner and outer peripheral rims 11—12 of the bowl cooperating to define a seat for a cap 13 which provides a closure for the bowl and in which the burner ports are formed.

For efficient distribution of the flame the burner ports preferably define an outer annular row comprising a large number of ports discharging angularly outwardly and upwardly, and an inner annular row consisting of relatively few ports 20 discharging angularly upwardly and toward the axis of the annular burner. As an instance of this arrangement the seat 11—12 may be an inverted truncated conical seat and the cap 13 may be a cooperating inverted truncated cone. 25 Alternate slots and ribs 14—15 of some appreciable length are formed in the peripheral surface of cone 13 adjacent its base, with the slots terminating at an annular rim which is at the base of the cone as shown at 16; and apertures 30 17 are formed in the cap 13 medially of the length of its axis and are inclined upwardly and inwardly toward said axis.

The seating surfaces between the body 1 and the cap 13 are preferably machined, whereby the cap fits tightly against seat 11 and the ribs 15 fit tightly against seat 12, the parts being preferably held in assembled relation by a clamping screw 18 extending through transverse spider 19 at the lower end of truncated cone 13 and engaging a spider 20 which extends across the annular body 1 adjacent its base. The bowl 16 is thus tightly closed except for the slots 14 and the apertures 17 which open into the bowl; and the slots 14 thus provide an outer annular row of burner ports circumferentially closely adjacent one another and thus forming a relatively large number of ports discharging upwardly and outwardly between the upper edge of the seat 12 and the annular rim 16. The apertures 17 provide inner burner ports, and are appreciably circumferentially spaced from one another so as to form a relatively small number of ports discharging upwardly and inwardly toward the axis of the 55

burner. The ports 14—17 thus cooperate for desired distribution of the total flame.

The outer ports being closely adjacent one another and extending the length of the slots 14, 5 the velocity of the combustible mixture will be appreciably reduced at these ports so as to avoid the flame being blown off; but the inner ports being appreciably spaced from one another and thus liable to have the flame blown off, means are 10 preferably provided for reducing the velocity at these ports. For this purpose a lug 21 may project from the surface of cap 13 and into the bowl 10 at each of the apertures 17, and the apertures open through the lugs into the bowl 10 15 with their upward and inward angularity uniformly prolonged, thereby forming discharge ports of appreciable length so as to reduce the velocity of the combustible mixture discharged through these elongated ports.

20 The construction as thus described also provides means for baffling the combustible mixture in bowl 10, in that the circumferentially spaced lugs 21 which project into the bowl interrupt free circumferential flow. The pipe 2 opens into the 25 side of the bowl so that the combustible mixture is directed around the bowl, and this circumferential flow is thus broken up by the baffles 21 for intimately mixing the gas and air, and the velocity of the fuel is somewhat retarded by the baffles 30 before it enters the discharge ports, and the baffles evenly distribute the fuel to the discharge ports.

The invention thus reduces the velocity of the 35 fuel at the burner ports, permitting the combustible mixture to be drawn into the fuel pipe 2 at high velocity so as to insure an efficient combustible mixture without danger of the flame being blown from the burner ports; and the invention also baffles the flow of the combustible mixture so as to insure uniform distribution and efficient combustion.

The burner is thus quiet in operation and produces an intense flame, due to proper proportioning of air and gas, even distribution of the combustible mixture, and prevention of flame blow off.

I claim:

1. In a burner, a bowl, a conduit for a combustible mixture opening into the side of the bowl 50 so as to direct the combustible mixture around the bowl, an inverted conical cap for the top of the bowl, the rims of the cap and bowl cooperating to define an annular series of burner ports communicating with the interior of the bowl, and baffle lugs depending from the cap into the bowl in appreciably circumferentially spaced relation and obstructing circumferential flow of the combustible mixture, each depending lug having a burner port extending therethrough the entire length of the lug and communicating with the interior of the bowl at the lower end of the lug, the said ports in the depending lugs being inclined

so as to discharge angularly upwardly and inwardly toward the axis of the inverted conical cap.

2. In a burner, a bowl for a combustible mixture, an inverted conical cap for the top of the bowl, the rims of the cap and bowl cooperating to define an annular series of burner ports communicating with the interior of the bowl, and baffle lugs depending from the cap into the bowl in appreciably circumferentially spaced relation 10 and obstructing circumferential flow in the bowl, each depending lug having a burner port extending therethrough the entire length of the lug and communicating with the interior of the bowl at the lower end of the lug, the said ports in the depending lugs being inclined so as to discharge angularly upwardly and inwardly toward the axis of the inverted conical cap.

3. In a burner, a bowl for a combustible mixture, an inverted conical cap for the top of the bowl, the rims of the cap and bowl cooperating to define an annular series of burner ports communicating with the interior of the bowl, and baffle lugs depending from the cap into the bowl in appreciably circumferentially spaced relation 25 and obstructing circumferential flow in the bowl, each depending lug having a burner port extending therethrough the entire length of the lug and communicating with the interior of the bowl at the lower end of the lug.

4. In a burner, a bowl for a combustible mixture, an inverted conical cap for the top of the bowl, the rims of the cap and bowl cooperating to define an annular series of burner ports communicating with the interior of the bowl, and lugs depending from the cap into the bowl in appreciably circumferentially spaced relation, each depending lug having a burner port extending therethrough the entire length of the lug and communicating with the interior of the bowl at 40 the lower end of the lug.

5. In a burner, a bowl for a combustible mixture, an inverted conical cap for the top of the bowl, the rims of the cap and bowl cooperating to define an annular series of burner ports communicating with the interior of the bowl, and lugs depending from the cap into the bowl in appreciably circumferentially spaced relation, each depending lug having a burner port extending therethrough and communicating at its lower end 50 with the interior of the bowl.

6. In a burner, a chamber for a combustible mixture, and lugs depending into the chamber in circumferentially spaced relation, each depending lug having a burner port extending therethrough 55 and communicating at its lower end with the interior of the chamber, said burner ports in the depending lugs being separate from one another throughout their entire length for separate discharge from their upper ends into the space above 60 the burner.

JOHN H. SATTLER.
